(57) **CLAIM**

The ornamental design for a reduced pressure treatment system, as shown and described.

DESCRIPTION

FIG. 1 is a front perspective view of a reduced pressure treatment system showing our new design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines illustrated in the drawings are for illustrative purposes only and form no part of the claimed design.

This design is not limited to the exact details shown in the drawings, since equivalents and colorable limitations thereof will be evidence to a person of ordinary skill in the art. Surface ornamentation, markings, and labels may be removed without departing from the scope of the design. Thus, within the scope of the appended claim, which is intended to cover only the ornamental and novel elements shown in the drawings, the invention may be practiced otherwise than as specifically shown and described herein.
